United States Patent Office.

JAMES WHITE, OF CLEVELAND, OHIO.

Letters Patent No. 93,571, dated August 10, 1869.

IMPROVEMENT IN APPARATUS FOR HOLDING HAT-BLOCKS.

The Schedule referred to in these Letters Patent and making part of the same.

To all whom it may concern:

Be it known that I, JAMES WHITE, of Cleveland, in the county of Cuyahoga, and State of Ohio, have invented certain new and useful Improvements in "Apparatus for Holding Hat and Bonnet-Blocks;" and I do hereby declare that the following is a full and complete description of the same, reference being had to the accompanying drawings, making a part of this specification, in which—

Figure 1 is a side view of the apparatus.

Figure 2, a view of the end.

Figure 3, a view of the top.

Like letters of reference refer to like parts in the several views presented.

This invention relates to an adjustable head or table, on which is placed and secured a hat or bonnet-block, whereon the hat or bonnet is pressed in the process of finishing, as hereinafter more fully described.

In fig. 1, A represents a shell or case, provided with a base, B, on which it stands, and is secured to the pressing-bench or table.

In said case is pivoted a standard, C, at the point *a*, whereon it vibrates, as and for a purpose hereinafter shown.

To the upper end of the standard is pivoted a head or table, D, at the point *b*, fig. 3, whereby said head may be turned around horizontally, for a purpose presently shown.

Attached to the under side of the head or table, and enclosing the standard, is a deep circular flange, E, also indicated by the dotted lines *c*, fig. 3, in which are cut more or less notches *e*, into which the end of the rod F is projected by a spring, *f*, and whereby said head or table is retained in any one position that may be required.

G, fig. 3, is a pair of adjustable clamps, secured to the surface of the table by a screw inserted in the

slots *h*, in which they slide for adjustment, and secured therein by the finger nut *i*, fig. 1.

The practical operation of this apparatus is as follows, viz:

The block on which the hat or bonnet is to be pressed is placed upon the head, between the clamps G, and by them embraced, and thereby held from sliding about. As the work of pressing progresses, the block and hat are adjusted to a convenient position and relation to the pressman by turning the head or table horizontally, which may be done by withdrawing the rod F from the notches *e*, thereby allowing the head to be turned around in either direction, as may be desired.

The head can be changed from a horizontal position to an oblique one, as indicated by the dotted lines *n*, by withdrawing the pin I, whereby the standard is secured in the case, and inserting the same in either of the holes *a*, as the obliqueness of the head may be required by the operator.

By this adjustable nature of the apparatus, it will be obvious that the block and hat can be turned to any desired position that the convenience of the operator may wish, and that without disturbing the block, it being held fast to the head or table by the clamps.

What I claim as my invention, and desire to secure by Letters Patent, is—

1. The adjustable head or table D, in combination with the notched flange E and rod F, when arranged and operating substantially as and for the purpose set forth.

2. The clamps G, adjustable head or table D, in combination with the notched flange E, rod F, and standards C, in the manner substantially as described and for the purpose set forth.
